NO. 36,411.

Patented July 7, 1903.

UNITED STATES PATENT OFFICE.

PHILEMON O. DICKINSON, OF NEWARK, NEW JERSEY.

DESIGN FOR A BROOCH OR BUCKLE-PLATE OR SIMILAR ARTICLE.

SPECIFICATION forming part of Design No. 36,411, dated July 7, 1903.

Application filed May 23, 1903. Serial No. 158,548. Term of patent 3½ years.

To all whom it may concern:

Be it known that I, PHILEMON O. DICKINSON, a citizen of the United States, residing at Newark, county of Essex, State of New Jersey, have invented a new, original, and ornamental Design for a Brooch or Buckle-Plate or Similar Article, illustrated in the accompanying drawing, which shows a front view of the same.

What I claim is—

The ornamental design for a brooch or buckle - plate or similar article, as herein shown.

PHILEMON O. DICKINSON.
